UNITED STATES PATENT OFFICE.

LEOPOLD STARK, OF BROOKLYN, NEW YORK.

TRIMMING.

SPECIFICATION forming part of Letters Patent No. 319,142, dated June 2, 1885.

Application filed December 12, 1884. (No specimens.)

To all whom it may concern:

Be it known that I, LEOPOLD STARK, of Brooklyn, in the county of Kings and State of New York, have invented certain new and useful Improvements in Trimmings, of which the following is a specification.

For the ornamentation of ladies' and children's garments of all kinds and other articles, the so-called "herring-bone stitch" has 10 been used, which is a kind of embroidery-stitch that imparts by simple means a very ornamental appearance to the parts to which it is applied. This herring-bone stitch has been extensively employed for a large number of 15 applications; but as it has to be produced with almost geometrical regularity it required specially-skilled hands, so as to produce the imitation of a herring-backbone, from which the 20 stitch has taken its name.

The object of this invention is to furnish a trimming ornamented with herring-bone stitches, the trimming forming an article of manufacture that is placed on the market in any width, length, and material, so that it can 25 be applied by anybody for producing the desired effect without requiring special skill.

The invention consists of a trimming formed of a foundation of plaited fabric, which is finished with herring-bone stitches of suitable 30 threads or cords.

In the accompanying drawings, Figure 1 represents a portion of a lady's or child's garment ornamented with my improved trimming. Fig. 2 is a side view of my improved trimming, 35 drawn on a larger scale. Fig. 3 is a horizontal section on line *x x*, Fig. 2, drawn on a still larger scale, showing the formation of the stitches; and Fig. 4 is a vertical transverse section on line *y y*, Fig. 2.

Similar letters of reference indicate corresponding parts.

In making my improved trimming a piece of suitable textile fabric, leather, or other suitable material is cut to the required width, on the 45 bias, and then folded or plaited from the edges inwardly by any approved folding and plaiting machine to the required width of the trimming to be produced. The plaited or folded

fabric *a* thus obtained forms the foundation upon which a series of herring-bone stitches, 50 *b*, of any suitable thread or cord is embroidered, as shown in Fig. 2. The stitches *b* unite the folded or plaited foundation, so that the folds or plaits cannot open or spread apart. A trimming, *A*, is thus obtained which is made 55 up in widths varying from one-eighth to two inches and more. The herring-bone stitches are produced either by hand or, when larger quantities of trimmings of a certain size are to be manufactured, on a machine specially constructed for this purpose. As the herring-bone stitch is well known to hands versed in 60 embroidering-work, and as the stitch is clearly shown in Figs. 2, 3, and 4 of the drawings, its formation does not require special description.

By supplying the market with a proper assortment of herring-bone-stitch trimmings in different fabrics and widths they can be used extensively in the manufacture of garments, 70 under-garments, and ladies' and children's articles of all kinds. A very ornamental trimming is thus furnished, which is ready for instant use, and which can be stitched onto any portion of the garment or other article desired 75 to be ornamented thereby.

By means of the trimming the application of the herring-bone stitch for ornamenting all kinds of articles is greatly enlarged, and the same placed within the reach of everybody. 80

Having thus described my invention, I claim as new and desire to secure by Letters Patent—

A trimming of a folded or plaited foundation of suitable fabric and herring-bone stitches 85 embroidered on the same and passed through the folds thereof, whereby the folded or plaited parts are united to the base part, substantially as set forth.

In testimony that I claim the foregoing as my invention I have signed my name in presence 90 of two subscribing witnesses.

LEOPOLD STARK.
